TELEPHONE HANDSET

Ernest S. McLarn, Manhasset, N. Y., assignor to
 International Standard Electric Corporation,
 New York, N. Y., a corporation of Delaware

Application April 13, 1942, Serial No. 438,774

13 Claims. (Cl. 179—103)

This invention relates to telephone hand sets, and more particularly to means for connecting a multi-conductor cord to the transmitter and receiver units of such hand sets.

An object of the invention is to provide an arrangement for cording hand sets which is simple, trouble-free, effective, and cheap, and which dispenses with all inserts, screw connections, and spring contacts. A further object is to render the operation of attaching the cord to a completely automatic one which permits no error in the connections and effects a substantial saving of time.

More specifically, it is an object of my invention to provide a cording arrangement in which the cord consists of a length of flat, ribbon-shaped multi-conductor cordage comprising a plurality of parallel conductors, which is threaded in a passageway or channel formed in the supporting shell of the hand set and extending down the handle from the transmitter capsule cavity to the receiver capsule cavity. The transmitter and receiver capsules are equipped with connectors provided with prongs which pierce the cord and make electrical contact with the proper tinsel or stranded conductors when the capsules are pressed home in their cavities by the act of screwing on the transmitter and receiver caps.

The above and other objects and features of my invention will be more fully understood from the following description taken in conjunction with the accompanying drawing in which

Fig. 1 is a sectional view of the hand set;

Fig. 2 is a section of the transmitter end of the hand set taken along the line 2—2 of Fig. 1;

Fig. 3 is a section of the handle of the hand set taken along the line 3—3 of Fig. 1;

Fig. 4 is a section of the receiver end of the hand set taken along the line 4—4 of Fig. 1;

Fig. 5 is a bottom view of the transmitter capsule; and

Fig. 6 is a bottom view of the receiver capsule.

Referring more particularly to Figs. 1 to 4, the hand set comprises a supporting shell 1 of molded thermoplastic material formed with a handle portion and two enlarged ends provided with cavities 2 and 3 for accommodating a transmitter capsule 6 and a receiver capsule 7. In the supporting shell 1 is a passageway or channel 4 which is open at the end at which the transmitter is located and extends from the base of the transmitter cavity through the handle portion to the base of the receiver cavity.

The cord 5 comprises three parallel tinsel or stranded conductors covered with a braided or

knitted fabric covering and vulcanized in a rubber insulation ribbon, the three conductors lying in a substantially common plane. One of the flat sides of the ribbon is formed with a longitudinally extending rib or ridge to ensure that the cord can be inserted in a hole of similar cross section in one correct way only whereby the different conductors will be connected to the proper connectors provided on the transmitter and receiver capsules in the hand set.

The channel 4 is formed with a cross section which corresponds substantially to the cross section of the cord 5 which is threaded therein and lies across the bottom of the transmitter and receiver cavities 2 and 3 in grooves or channels.

The transmitter capsule 6 is provided with two connectors which are screwed or otherwise secured to the capsule case and which are formed with rearwardly extending sharpened prongs 10, 11. As shown, each connector is formed with three prongs which extend parallel to the conductors of the cord 5 when it is inserted in the channel 4, but obviously a greater or lesser number of prongs may be employed. The connectors are electrically connected to the back and front electrodes (not shown) of the transmitter. The prongs 10, 11 are arranged symmetrically with respect to the circular base of the transmitter capsule 6, the case of which is preferably made of molded thermoplastic material and is formed with a pair of diametrically opposite ridges 14, 15 which fit in corresponding guiding grooves provided in the wall of the transmitter cavity 2 when the capsule is inserted in its cavity. Since the transmitter is intended to be connected to the two outer conductors of the cord 5, the two ridges 14, 15 and their guiding grooves may be alike, as the transmitter may assume either of two positions displaced 180°. The act of screwing down the cap 8 presses the transmitter capsule 6 home in its cavity and forces the prongs 10, 11 through the insulation of the cord 5 into the tinsel of the two outer conductors.

The receiver capsule 7, the case of which is also preferably of molded plastic material, also has mounted upon its base a pair of connectors also provided with rearwardly projecting prongs 12, 13. The aforesaid connectors are electrically connected to the ends of the receiver coil (not shown). The prongs 12 and 13 are asymmetrically arranged with respect to a diameter of the circular base of the capsule, since it is desired that they make electrical contact with the center conductor and one outer conductor, re-

spectively, of the cord 5, as shown in Figs. 4 and 6. The casing of the receiver capsule 7 is formed with a pair of ridges 16, 17, and the wall of the receiver cavity 3 with corresponding guiding grooves, which are of different size to ensure that the receiver capsule 7 can be inserted into its cavity in one position only. The act of screwing down the cap 9 on the receiver capsule 7 forces the prongs 12 and 13 into the center conductor and one of the outer conductors.

It will be appreciated that if desired, the prongs associated with the receiver capsule may be arranged to make contact with the two outer conductors, and those of the transmitter capsule with the center conductor and one of the outer conductors of the cord 5. Moreover, if desired, only one guiding ridge and groove may be provided for ensuring that the transmitter capsule or the receiver capsule is positioned correctly in its cavity.

The casing of the transmitter capsule 6 is also provided on its base with rearwardly projecting snubbers 18 which, when the capsule is pressed home by the cap 8, compress the cord 5 at points along its length in front of and in back of the connecting prongs 10, 11, thus holding the cord immovable, and preventing noise which might otherwise develop due to slight displacement of the tinsel or stranded conductors with respect to the contacting prongs when the hand set is in use.

A steel mandrel is used to core out the handle of the hand set to provide the channel 4 for the cord 5, and in order that it may be withdrawn from the molding it must be slightly tapered towards the receiver end, thus enlarging towards the transmitter end. Although, therefore, the cord 5 may fit snugly in the portion of the channel 5 beneath the receiver capsule 7, there will be some slight play in the part of the channel beneath the transmitter capsule 6. In order, therefore, to compel the centering of the cord 5 correctly beneath the prongs 10, 11, the contacting edges of the snubbers 18 are hollowed out to conform with the contour of that side of the cord upon which they press when the cap 8 is screwed down. The snubbers 18 may be constituted by molded projections on the base of the molded transmitter capsule casing. If desired, snubbers may also be provided on the base of the receiver capsule for a similar purpose.

While I have described particular embodiments of my invention for the purposes of illustration, it should be understood that various modifications and adaptations thereof may be made within the spirit of the invention as set forth in the appended claims. For example, any one of the three cord conductors may be employed as the common conductor. Thus, the prongs on one capsule may be so positioned as to make contact with the center conductor and one outer conductor and the prongs on the other capsule so positioned as to make contact with the center conductor and the other outer conductor.

What I claim is:

1. A telephone hand set comprising a transmitter element, a receiver element, a supporting shell therefor formed with a handle, a pair of cavities for accommodating the transmitter and receiver elements respectively, and a channel open at one end of said supporting shell and extending through said handle from said transmitter cavity to said receiver cavity, a conductor cord comprising a plurality of parallel conduc-

tors threaded as a whole in said channel, a plurality of electrical connectors mounted on said transmitter element, and a plurality of electrical connectors mounted on said receiver element, each said connector having at least one sharpened prong, and means for forcing said prongs into said cord to make electrical contact with the proper conductors.

2. A telephone hand set comprising a transmitter capsule, a receiver capsule, a supporting shell therefor formed with a handle, a pair of cavities for accommodating said transmitter and said receiver capsules respectively, and a channel open at one end of said supporting shell and extending through said handle from the base of said transmitter cavity to the base of said receiver cavity, a conductor cord comprising a plurality of parallel conductors threaded as a whole in said channel, a plurality of electrical connectors mounted on the base of said transmitter capsule, and a plurality of electrical connectors mounted on the base of said receiver capsule, each said connector having at least one rearwardly projecting prong, said prongs being so positioned that when said transmitter and receiver capsules are pressed home into their respective cavities said prongs are forced into said cord to make electrical contact with the proper conductors.

3. A telephone hand set according to claim 2, wherein at least one of said capsules is provided on its base with at least one projecting member so shaped and positioned that when said capsule is pressed home in its cavity said projecting member engages and compresses said cord.

4. A telephone hand set according to claim 2, wherein said transmitter capsule is provided on its base with projecting members so shaped and positioned that when said capsule is pressed home in its cavity said projecting members engage and compress said cord on each side of the connecting prongs provided on said transmitter capsule.

5. A telephone hand set according to claim 2, wherein said transmitter capsule is provided on its base with projecting members so positioned that when said capsule is pressed home in its cavity said projecting members engage and compress said cord in said channel on each side of the connecting prongs provided on said transmitter capsule, the edges of said projecting members being so shaped that during this operation they correctly center said cord beneath the connecting prongs provided on said transmitter capsule.

6. A telephone hand set according to claim 2, wherein each said connector is formed with a plurality of prongs the points of which are disposed along a line extending parallel with said conductor cord.

7. A telephone hand set according to claim 2, wherein said conductor cord comprises three parallel conductors, said prongs on one of said capsules being so positioned as to make contact with the two outer conductors of said cord, and said prongs on the other capsule being so positioned as to make contact with the center conductor and one of the outer conductors.

8. A telephone hand set according to claim 2, wherein said transmitter and receiver capsules are each provided with at least one guiding ridge and said transmitter and receiver cavities are each formed with at least one corresponding guiding groove so positioned as to ensure that said prongs on said transmitter and receiver

capsules register with the proper cord conductors when the capsules are inserted and pressed home in their respective cavities.

9. A telephone hand set according to claim 2, further comprising peripheral lips on said transmitter and receiver capsules, seatings for said lips on said supporting shell at the edges of said transmitter and receiver cavities, and threaded caps formed with abutments which when said caps are screwed onto said shell force said lips against said seatings, the distance from the points of said prongs to said lips being such that when said lips are forced against their seatings by the act of screwing on said caps, the said prongs are forced into said cord and make electrical contact with the proper conductors.

10. A telephone transducer comprising a supporting shell, a transducer element, a cavity in said shell for accommodating said transducer element, a channel formed in the base of said cavity, a conductor cord comprising a plurality of parallel conductors positioned in said channel, a plurality of electrical connectors mounted on the base of said transducer capsule, each said connector having at least one rearwardly projecting prong, a peripheral lip on said transducer capsule, a seating for said lip on said supporting shell at the edge of said cavity, and a threaded cap formed with an abutment which when said cap is screwed onto said shell forces said lip against said seating, the distance from the points

of said prongs to said lip being such that when said lip is forced against its seating by the act of screwing on said cap, the said prongs are forced into said cord and make electrical contact with the proper conductors.

5 11. A telephone transducer according to claim 10 wherein said transducer capsule is provided on its base with at least one projecting member so shaped and positioned that when said lip is forced against its seating said projecting member engages and compresses said cord.

10 12. A telephone transducer according to claim 10 wherein said transducer capsule is provided on its base with projecting members so positioned that when said lip is forced against its seating said projecting members engage and compress the cord in said channel on each side of said prongs, the edges of said projecting members being formed with a recess conforming to 15 the contour of said cord whereby when said cap is screwed onto said shell said members correctly center said cord beneath said prongs.

15 13. A telephone hand set according to claim 2, wherein said conductor cord comprises three parallel conductors, said prongs on one of said 20 capsules being so positioned as to make contact with the center and one outer conductor, and said prongs on the other capsule being so positioned as to make contact with the center and 25 the other outer conductor.
